(57) **CLAIM**

The ornamental design for a flow regulator, as shown and described.

DESCRIPTION

FIG. 1 is a top isometric view of the flow regulator of our design;

FIG. 2 is a top plan view thereof;

FIG. 3 is a front elevational view thereof, the rear, right and left views being identical thereto; and,

FIG. 4 is an exploded top isometric view thereof.

The broken lines shown in the drawings depict environment and form no part of the claimed design.

1 Claim, 4 Drawing Sheets

FIG. 1

FIG. 2

FIG. 3

FIG. 4
